(57) **CLAIM**

The ornamental design for a collapsible bottle, as shown and described.

DESCRIPTION

FIG. 1 is a perspective view of the collapsible bottle; FIG. 2 is a front plan view of the collapsible bottle of FIG. 1; FIG. 3 is a back plan view of the collapsible bottle of FIG. 1; FIG. 4 is left side view of the collapsible bottle of FIG. 1; FIG. 5 is right side view of the collapsible bottle of FIG. 1; FIG. 6 is a top view of the collapsible bottle of FIG. 1; and, FIG. 7 is a bottom view of the collapsible bottle of FIG. 1. The broken lines showing the spout, carabiner, and bottom portion of the collapsible bottle are for illustrative purposes only and form no part of the claimed design.
